FIG. 2

FIG. 3

FIG. 4

FIG. 5

FIG. 6

FIG. 7

FIG. 8

FIG. 9

FIG. 1 is a perspective view of the golf putter head showing my new design.

FIG. 2 is a front perspective view taken from the left side of the foot.

FIG. 3 is a front perspective view taken from the right side of the foot.

FIG. 4 is a top plan view thereof.

FIG. 5 is a bottom plan view thereof.

FIG. 6 is a right-side view thereof.

FIG. 7 is a left-side view thereof.

FIG. 8 is a front-end view thereof.

FIG. 9 is a rear-end view thereof.

The characteristic features of my design reside in the particular striking face configuration located on the outside of the foot and combined with the four toed exaggerated foot form as shown.

I claim:

The ornamental design for a golf putter head, as shown and described.
